M. GONICK

SAFETY COLLAR AND CUFF BUTTON

Filed July 3, 1922

INVENTOR
Max Gonick
BY
W. J. Priswells
ATTORNEY

UNITED STATES PATENT OFFICE.

MAX GONICK, OF NEW YORK, N. Y.

SAFETY COLLAR AND CUFF BUTTON.

Application filed July 3, 1922. Serial No. 572,644.

To all whom it may concern:

Be it known that I, MAX GONICK, a citizen of the United States, and a resident of New York, borough of Bronx, in the county of Bronx and State of New York, have invented certain new and useful Improvements in a Safety Collar and Cuff Button, of which the following is a full, clear, and exact specification.

10 This invention relates more particularly to a class of fastening devices. My invention has for its object primarily to provide a collar and cuff button adapted to be used for detachably fastening connectible parts of a garment worn by a person, such as applying a collar to the neckband of a shirt or waist or connecting the cuffs of the garment whereby the parts of the cuff may be separated or the collar unattached without danger of accidental loss of the button. The invention contemplates mainly the provision of a base member and a head member formed on the ends of a shank or post having two oppositely protruding bosses or annular flanges with sockets in their centers. In the free edges of the bosses are spaced notches to provide spaced stop members or teeth. In the sockets of the bosses are pivotally seated the ends of an approximately U-shaped spring clamp which is normally disposed in movable straddle position over the head of the post to allow passage of the clamp and head of the button through the button hole of a garment and then swung toward the base member for preventing accidental separation of the button from the garment. The arms of the U-shaped clamp are spaced for yieldingly engaging the teeth of the bosses of the post when straddling the head and also when swung toward the base member for movably holding the clamp in its adjusted positions.

15 A further object of the invention is to provide a safety collar and cuff button of a simple and efficient construction which may be made in any appropriate size and shape.

With these and other objects in view, the invention will be hereinafter more fully described with reference to the accompanying drawing forming a part of this specification in which similar characters of reference indicate corresponding parts in all the

views and will then be pointed out in the 55 claims at the end of the description.

In the drawing, Figure 1 is an elevation of one form of safety collar button embodying my invention.

Fig. 2 is an elevation of the button showing its clamp swung to a clamping position.

Fig. 3 is an elevation of the button with the clamp removed.

Fig. 4 is an elevation of the clamp, and

Fig. 5 is an elevation of the device made 65 in the form of a cuff button.

The device or button when made of a form for use to removably attach especially a collar on the neckband of a shirt, waist or other garment has a post or shank 10 70 which is preferably straight and may be cylindrical or of other appropriate shape. On one end of the post 10 may be a base member 11 in the form of a laterally protruding annular flange or plate, such as is 75 commonly used on buttons of this class, and on the other end of the post is a head member 12 which may be in the form of a ball or other shape.

Projecting in opposite directions from opposite parts of the post 10 in spaced proximity to the base member 11 are two corresponding bosses or annular flanges 13 and 14, each having in its center a socket 15. In the free edges of the bosses are corresponding spaced stops or teeth, as 16, which are provided by notching, as at 17, 17^a and 18, 18^a, the edge of each boss, one notch being preferably at each quadrant of the circumference of the boss so that the pair of notches 17, 17^a of each boss are in register as well as being disposed crosswise of the post 10, while the pair of notches 18, 18^a of each boss are also in register and disposed on a plane similar to the plane of the 95 post.

In the sockets 15 of the bosses 13 and 14 are pivotally disposed the lugs, as 19 and 20, protruding toward each other from the arms 21 and 22 of a clamp 23 which is approximately U-shaped to provide a spanning or arch member 24 on one of the ends of the arms 21 and 22. The arms 21 and 22 may be of shapes and thicknesses adapted to removably fit in the notches 17, 17^a and 18, 18^a 105 of the bosses of the post 10, or on the opposed parts of the arms in proximity to the lugs 19 and 20 may be two teeth, as 25 and

26, respectively which are spaced from each other for removably fitting in the notches to engage the stops or teeth 16 of the bosses. The clamp 23 is made of spring metal, and the arms 21 and 22 are so spaced that the teeth 25 and 26 are normally seated in the notches of the bosses to prevent accidental movement of the clamp.

When in normal position the clamp is disposed in straddle position over the head member 12 of the post 10 of the button with the teeth 25 and 26 being seated in the pairs of notches 18 and 18^a of the bosses 13 and 14. To use the button for fastening the separated parts of a person's garment, the head member 12 and the clamp is then passed through an opening or button hole in one end of the garment, and the clamp is swung to a right-angular position relative to the post so that the teeth 25 and 26 of the arms 21 and 22 of the clamp will be yieldingly moved into the pairs of notches 17 and 17^a of the bosses 13 and 14. The button will thereby be held to one end part of the garment against liability of being lost, and by passing the head member 12 through an opening or button hole in the other end of the garment the ends of the garment will be detachably fastened. When the device is made for use as a cuff button, as shown, in Fig. 5 the formations of its parts are similar to those of the collar button, excepting that the shank or post 10 and the clamp 23 are curved or bent in an appropriate manner, and the base member 11 as well as the head member 12 may also be made in either plain or ornamental designs as occasion requires.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I

claim as new and desire to secure by Letters Patent:

1. A collar and cuff button, comprising a post having on its ends a base member and a head member, said post having in spaced proximity to the base member two oppositely projecting substantially circular bosses, each having two spaced pairs of notches in its free edge at quadrants thereof, and a substantially U-shaped spring clamp having on the free ends of its arms protruding lugs pivotally seated in the sockets of the bosses whereby the clamp is adapted to be normally disposed in movable spanning position over the head of the post for being swung toward and from the base member and the arms of the clamp having teeth yieldingly engaging two pairs of the notches of said bosses when straddling the head member and also for yieldingly engaging the other two pairs of the notches when swung toward the base member.

2. A collar and cuff button, comprising a post having on its ends a base member and a head member, said post having in spaced proximity to the base member two oppositely projecting substantially circular bosses, each having teeth in its free edge at quadrants thereof, and a substantially U-shaped spring clamp having on the free ends of its arms protruding lugs pivotally seated in the sockets of the bosses, whereby the clamp is adapted to be normally disposed in movable spanning position over the head of the post for being swung toward and from the base member and the arms of the clamp being spaced for yieldingly engaging a number of the teeth of said bosses when straddling the head member and also for yieldingly engaging a number of the teeth when swung toward the base member.

This specification signed and witnessed on this 1st day of July A. D. 1922.

MAX GONICK.
